UNITED STATES PATENT OFFICE

148,016

DESIGN FOR A SLED

William Flajole, Detroit, Mich.

Application May 23, 1946, Serial No. 129,997

Term of patent 14 years

(Cl. D34—15)

To all whom it may concern:

Be it known that I, William Flajole, a citizen of the United States, residing at Detroit, in the county of Wayne and State of Michigan, have invented a new, original, and ornamental Design for a Sled, for which the following is a specification, reference being had to the accompanying drawing, forming part thereof, in which:

Fig. 1 is a perspective view of the sled, showing my new design;

Fig. 2 is a side elevational view thereof on a reduced scale;

Fig. 3 is a front elevational view thereof on a reduced scale; and

Figure 4 is a top plan view thereof on a reduced scale.

I claim:

The ornamental design for a sled, substantially as shown.

WILLIAM FLAJOLE.
